V. C. LUPPERT

LEAF SUPPORT

Filed Feb. 2, 1925

Patented Dec. 6, 1927.

1,651,825

UNITED STATES PATENT OFFICE.

VALENTINE C. LUFPERT, OF WILLIAMSPORT, PENNSYLVANIA.

LEAF SUPPORT.

Application filed February 2, 1925. Serial No. 6,407.

This invention relates to drop leaf supports for tables, desks, etc., and one object is to provide a simple support which may be easily adjusted to hold the leaf in a raised position for use or to drop into a pendent position out of the way when its use is not desired. Other objects of the invention will appear incidentally in the course of the following description, and the novel features 10 will be particularly pointed out in the claims following the description.

In the accompanying drawing, Figure 1 is a bottom plan view of a portion of a table top and a leaf, the leaf being held in raised position by a device embodying my invention:

Figure 2 is a longitudinal section of the same;

Figure 3 is a transverse section;

Figure 4 is a view similar to Figure 2 showing the leaf dropped;

Figure 5 is a detail elevation of one of the guides with an adjusting device thereon;

Figure 6 is a detail elevation of the stop 25 guide;

Figure 7 is a detail perspective view of the slide.

Referring more specifically to the drawing, the numeral 1 designates a portion of the 30 top of a table, desk, typewriter stand, or similar article having a drop leaf 2 connected thereto by hinges 3, a rim 4 being secured to the underside of the top 1 adjacent the edge thereof as is usual. Angle brackets 5 are secured in the angle defined by the rim 35 and the table top, as shown, to reenforce the rim at opposite sides of the point where the slide passes therethrough.

Midway between the angle brackets, a 40 notch 6 is cut in the upper edge of the rim and a guide bracket 7 is secured to the side of the rim at said notch. This guide bracket may be secured to either side of the rim and consists, primarily, of a metal plate having 45 openings 8 at its ends through which screws or the like may be passed in the rim to secure the bracket in place. As shown in Figure 3, the bracket is so placed that its upper edge abuts the under side of the table top, and in its upper edge is formed a central notch 9, shown most clearly in Figure 5, which registers with the notch 6 in the rim. A tongue 10 rises centrally from the floor 50 of the notch 9 to a point about midway the height of the notch, and a lug 11 projects laterally from the upper extremity of the

tongue, a similar lug 12 projecting from the bracket below the lug 11, as shown. Threaded openings are formed through the lugs 11 and 12 in axial alinement to receive an adjusting screw 13, as shown and as will be understood.

The leaf support consists of a slide 14 of inverted U-shape or channel formation inserted through the notches 6 and 9 with its 60 top or cross web bearing against the bottom of the table top and its side webs engaging between the sides of the tongue 10 and the side walls of the notch 9, the tongue thereby fitting within the channel of the slide so that 65 the latter will be positively guided as it is moved in or out. In the outer end of the slide is fitted a ring 15 which serves as a handle for the slide and also as a stop to prevent it being pushed entirely through the 70 rim when it is retracted, as will be understood on reference to Figure 4. Spaced inwardly from the rim and alined with the bracket 7, a guide and stop bracket 16 is secured to the under side of the table top to 75 guide and support the inner end of the slide.

The bracket 16 consists of a flat plate having a notch 17 in its upper portion through which the slide 14 passes, and also having 80 ears 18 through which fastening devices are 85 inserted into the table top. At its inner end, stop lugs 19 project from the sides of the slide to impinge against the inner side of the stop bracket 16, as shown in Figure 1, and thereby limit the outward movement of 90 the slide.

When the slide is pushed inward, as shown in Figure 4, the leaf 2 is permitted to swing downward. If the leaf is to be used, it is 95 swung upward and the slide is drawn out 100 under it to support it as shown in Figures 1 and 2. Should the leaf not lie perfectly true or flush with the table top, a few turns of the adjusting screw 13 will raise or lower the outer end of the slide so as to bring the 105 leaf into the proper plane. The slide is of such proportions that it may be easily drawn in or out when desired but is not apt to be accidentally moved inwardly and prematurely drop the leaf. While the slide will 110 firmly support the leaf when drawn out, it is light and inexpensive and of such form that it may be readily stamped from sheet metal, and the brackets through which it moves may be likewise expeditiously and cheaply produced.

Having fully described my invention what

I claim as new and desire to secure by Letters Patent, is:—

1. The combination with a table top, and a drop leaf hinged thereto, of spaced aligned guides on the table top, a slide movable through the guides to support the leaf in raised position, means on the slide to engage the respective guides and limit the movement of the slide in either direction, and 10 means on the outer guide to vertically adjust the outer end of the slide.
2. The combination with a table top, and a drop leaf hinged thereto, of guide brackets on the under side of the table top having notches in their upper edges, one of the brackets having a tongue rising centrally from the floor of the notch therein, and a channeled slide mounted through the notches in the brackets and spanning said tongue 15 and adapted when moved outwardly to support the leaf in raised position.
3. The combination with a table top, and a drop leaf hinged thereto, of guide brackets on the under side of the table top having notches in their upper edges, one of the brackets having a tongue rising centrally from the floor of the notch therein, a lateral lug at the upper end of the tongue, a lateral lug below the tongue, a channeled slide 20

mounted through the notches in the brackets 30 and spanning said tongue and adapted when moved outwardly to support the leaf in raised position, and an adjusting screw threaded through the lugs and bearing upon the slide to vertically adjust the outer end 35 of the same.

4. The combination with a table top, and a drop leaf hinged thereto, of guide brackets on the under side of the table top, a channeled slide mounted through said guides 40 and adapted when moved outward to support the leaf in raised position, and lateral lugs on the sides of the slide at the innermost end arranged to impinge against the inner guide to limit the outward movement 45 of the slide, one of the guides having an element fitting within the channel of the slide.

5. The combination with a table top, and a drop leaf hinged thereto, of guides on the under side of the table top, a channeled slide 50 mounted through the guides and adapted to support the leaf in raised position, and a screw mounted on one of the guides and bearing against the slide within the channel thereof. 55

In testimony whereof, I have signed this specification.

VALENTINE C. LUPPERT.
